FLUID HEATER

Frank H. Praeger, Merion, Pa., assignor to Alcorn Combustion Company, Philadelphia, Pa., a corporation of Delaware

Application November 24, 1943, Serial No. 511,758

13 Claims. (Cl. 122—356)

This invention, relating to the heating of fluids, particularly hydrocarbon oil and its derivatives, has for an object the provision of a heater characterized by the uniformity of its heat application and a flexibility in operation which makes possible the achievement of widely varying heating requirements.

It has long been recognized that the heating of certain fluids such as petroleum and its derivatives presents a relatively difficult problem. The stream of petroleum must not be overheated at any point during its travel through the heating tubes. If too much heat is applied to a limited portion of a tube, the oil film at that point is raised to a temperature where parasitic cracking of the hydrocarbon within the tube occurs, and carbon or tarry products are formed. Such material forms a deposit on the wall of the tube. Any deposition on or within a tube lowers the rate of heat transfer and correspondingly increases the temperature of the tube at that point. The situation becomes progressively worse; the overheated portion becomes dangerously hot. The foregoing phenomena have been recognized as a cause of shut-down and sometimes of tube failure.

It is required that the heat generated within any fire chamber should be limited to an amount such that there occurs a minimum of such "hot spots." For example, if a fluid-conducting tube were disposed within a flame like that from a blow torch at the point of flame impingement, the heat application would be exceedingly high and excessive, and on all other points on the tube there would be no heat application. Hence the average rate of heat application to the tube would be exceedingly low and it would be of little value as an efficient heating tube, as compared with one where heat is uniformly applied over the entire tube at the maximum permissible rate for the particular heating duty.

It is accordingly an object of the present invention to provide a heater in which the heat application is relatively uniform throughout entire banks of tubes and uniformly controllable over a wide range.

In carrying out the invention in one form thereof, two vertical banks of horizontally disposed tubes are located adjacent the opposite side walls of a fire chamber. A plurality of vertically spaced burners are arranged to direct streams of still-burning combustion gases between and generally parallel to the banks of tubes. By means of an internal chimney structure the streams of still-burning gases flow smoothly and evenly lengthwise of the fire chamber and between the

banks of tubes. After the gases have given up a part of their heat by radiation to the opposed banks of tubes, they are directed more and more toward the respective banks of tubes thereby to equalize the heat application throughout the lengths of the tubes. The internal chimney structure is formed by walls which approach each other to form therebetween openings through which the gases are withdrawn from the fire chamber. Because the internal chimney extends from the floor to the roof of the fire chamber a greater stack effect is exerted on the gases adjacent the floor and compensation is thereby provided against the tendency of the gases to rise in the chamber proper. To accentuate this effect the space between the walls near the floor may be greater than at the top thereof. This insures the flow from the fire chamber of approximately the same volume of gases per unit of area from the floor to the roof of the fire chamber. In a preferred form of the invention, the internal chimney structure divides a heating chamber into two fire chambers, provided with burners at opposite ends thereof. A plurality of said fire chambers may be disposed side by side each with its own internal chimney structure. A convection section common to the several fire chambers may be located with its tubes extending at right angles to the vertical banks of horizontal tubes.

Other features and advantages of the invention will become apparent and will be presented in the following more detailed description, taken in conjunction with the drawings in which:

Fig. 1 is a horizontal sectional view of a multi-cell heater embodying the invention;

Fig. 2 is a sectional elevation taken on the line 2—2 of Fig. 1;

Fig. 3 is a sectional elevation taken on the line 3—3 of Fig. 1;

Fig. 4 is a fractional view taken on the line 4—4 of Fig. 3;

Fig. 5 is a detailed view of a typical fuel burner and associated combustion chamber;

Fig. 6 is a horizontal sectional view of another embodiment of the invention; and

Fig. 7 is a sectional elevation taken on line 7—7 of Fig. 6.

Referring to the drawings I have shown my invention in one form as applied to a multicell heater comprising a plurality of fire chambers 10—17. Inasmuch as the respective fire chambers are of a substantially identical construction only two of them, the chambers 12 and 13, need be described in detail. They are formed by means of a plurality of vertically disposed horizontal

tubes forming sidewall banks 19 and 20. The respective ends of the tubes of the bank 19 terminate within header boxes 21 and 22, and the respective ends of the tubes 20 terminate within header boxes 23 and 24. The headers themselves are not shown but it is to be understood that headers are provided to connect the tubes in series or parallel for flow of fluid therethrough.

As shown in Figs. 1 and 2 a plurality of burner openings 26, spaced vertically one above the other, are located intermediate the tube banks 19 and 20 at one end of the heater; and a plurality of burner openings 27 are similarly located at the opposite end of the heater. As shown in Fig. 5 each burner opening is provided with a fuel burner 28 which operates under the control of a valve 29 connected by a pipe 30 to a suitable source of fuel which may be either oil or gas or a combination of the two. Fuel projected by the burners through the burner openings, each preferably in the form of a venturi for induction of air, is partially burned in muffles or combustion chambers 31 and 32 respectively coextensive with the burner openings 26 and 27. By providing the relatively long and narrow vertically disposed muffles 31 and 32, a column or a solid vertical stream of the still burning gases is directed outwardly and into the fire chambers 12 and 13, and there is little tendency for the gases to move from the column toward or to contact the sidewall tubes 19 and 20. The vertically elongated body of gases from the vertical and elongated rectangular muffles 31 and 32 moves centrally of the respective fire chambers 12 and 13 until it approaches the structure forming an internal flue 33.

This structure consists of walls 34 and 35 which extend toward each other and toward the elongated muffle 31, the two walls at the juncture presenting an apex 36 directly opposite the muffle 31. Similarly walls 37 and 38 form the apex 39 which is on a line with the elongated muffle 32. The walls 34-35 and 37-38, Fig. 2, extend from the bottom or floor of the heater 48 to the top or roof 41. They are preferably made of a heat refractory material such as first quality fire brick. These walls are self-supporting, although additional steel supports may be included, if desired. Relatively short ends of the walls 34 and 37 extend parallel to the axes of the tubes 19 and 20 and approach each other to form a narrow opening 42 which is open and unobstructed from the bottom to the top of the fire chambers. Similarly, like ends of the walls 35 and 38 approach each other to form a like narrow opening 43 adjacent the tube bank 20. The outer faces of the walls 34 and 35 serve two functions. They reflect heat toward the respective tubes 19 and 20 and thereby serve to equalize the intensity of the heat application. More particularly, it will be understood that as the gases travel from the elongated muffle 31 toward the central flue, the absorption of radiant heat by the vertical tube banks 19 and 20 lowers the temperature of the gases. The reflected radiant heat from the surfaces 34 and 35 is applied to the tubes 19 and 20 in the zone or region where the heat application has been decreased and adds to the direct radiant heat received by these heat absorbing areas. The added radiant heat tends to equalize the heat application to tubes 19 and 20. The inclination of the walls 34 and 35 not only controls the direction of the re-radiated heat but it also serves to divide the column of combustion gases and gradually and increasingly deflects the gases into convective-

tion heat exchange with the tube surfaces in the region or vicinity of the openings 42 and 43. The superimposed convection heat transfer completes substantial compensation for the cooling of the combustion gases. As a result, substantial uniform heating of the entire lengths of the tubes of the banks 19 and 20 is achieved. The gases from the elongated muffles 31 and 32 after passage along the respective faces of the walls 34-35 and 37-38 flow through the openings 42 and 43 and into the internal flue provided by the space between the inner faces of these walls. This space or the internal flue proper is subjected to stack draft in manner to be later explained.

As shown in Fig. 2, the fire chambers may be relatively high. By providing the internal chimney with the side openings 42 and 43 extending from the bottom to the top of the respective fire chambers, substantially uniform flow of the gases from bottom to top of the heater is achieved. The internal chimney itself produces a draft or a stack effect, which increases from the top to the bottom, being a maximum at the floor of the heater. The more highly heated gases in the respective fire chambers 12 and 13 will tend to rise, in contrast with the tendency of gases of lower temperature. This tendency of the hotter gases to rise and to flow along the upper part of the fire chamber is compensated for by the varying stack-draft applied to each fire chamber. In this manner, the combustion gases from the elongated muffles 31 and 32 are caused to move in fairly well defined lines of flow through the center of the respective fire chambers 12 and 13, to divide around the projecting walls of the inner chimney 33 and evenly and uniformly to exit through the openings 42 and 43. The heat application to the tubes 19-20 is substantially entirely by radiation over the larger part of the heat absorbing areas thereof, with the addition of convection heat as the gases are deflected by the walls of the inner chimney 33. The inner chimney 33 with its side openings 42 and 43 provides the additional advantage of preventing radiant heat loss from the fire chambers 12 and 13. In many respects radiant heat may be compared with the behavior of light rays. If the openings 42 and 43 were directly opposite the burners or opened directly into the fire chambers 12 and 13 radiant heat would be radiated directly into the chimney 33 and a relatively large proportion thereof would appear in the convection section. Some of this radiant heat would be lost and that applied to the convection tubes would tend to overheat them. By providing the openings 42 and 43 adjacent the sidewall tubes 19 and 20 and at right angles to the direction of flow of the gases, they are so located as to minimize the loss of radiant heat. If the muffles 31 and 32 were considered as search lights it would be seen at once that very little light would enter the openings 42 and 43 whereas if they were located directly in the beam the full intensity of the light would be directed into them. In this respect, the action of the radiant heat is quite similar.

The walls 34-35 and 37-38 join the roof 41 as shown in Fig. 2. The roof itself is provided with a rectangular opening 44, Figs. 2-4, which is smaller than the internal flue but centrally located with respect to it. A cooperating external duct 45, which leads to a stack (not shown) indicated at 46 subjects the internal flue 33 to a stack-draft. The tapering sides or gradually increasing cross-sectional areas of the openings 42 and 43 apply the stack-draft with a maximum

effect from the floor to the roof, further to insure uniformity of flow of the gases across each fire chamber from the muffles to the exit openings.

As already stated, a plurality of fire chambers 10-17 have been illustrated in the embodiment of the invention comprising Figs. 1-4. Thus the fire chambers 10 and 11 are provided with the internal flue 47; the fire chambers 14 and 15 with an internal flue 48; and the fire chambers 16 and 17 are provided with an internal flue 49 all of identical construction with the flue 33 which has already been described at length. Directly above each of the respective internal flues, Fig. 4, are rectangular openings 50, 51 and 52.

A further feature of the invention resides in the provision of a convection section common to the internal flues 47, 33, 48 and 49. Combustion gases withdrawn through the openings 50, Figs. 3 and 4, expand along the widening opening and are evenly distributed and directed by baffles 53 and 54 into a bank of convection tubes 55, only one of which is shown in Fig. 3. Similarly, additional baffles 56-58 distribute and guide the gases issuing from the openings 44, 51 and 52 so that they flow uniformly against and over the tubes of the convection bank 55. As shown in Fig. 2 the tubes of the bank 55 may be spaced apart to a greater degree than the tubes of a second section 55a of the convection bank. The banks 55 and 55a are disposed at right angles to the radiantly heated tube banks 19 and 20 and to the corresponding vertically disposed horizontal rows of tubes of the remaining fire chambers. Such a disposition of the convection bank lends itself to economical construction without sacrifice of heating efficiency. For example, the external duct 45 which forms the walls of the convection section is located directly above the respective internal flues. There is a minimum radiation loss and a minimum loss of draft. The arrangement as a whole is highly effective.

Further structural features of the heater are indicated in conventional and partly diagrammatic manner. The necessary trusses to support the structure are of fairly simple character. A weather roof 64-65 protects the supporting structure as well as the refractory roof 41 of the fire chambers proper. Moreover, the disposition of the convection bank below the roof of the heater tends to minimize radiation losses.

The foundation for the heater is more or less conventional, the usual footings 61-70 of concrete being provided, with the floors 71, 73 and 76, each comprising a sand-fill through which air conducting pipes 72 may extend. As shown, the sand-fill is overlaid with a covering which may be of firebrick.

Again referring to Fig. 1 it will be observed that between the adjacent fire chambers 14 and 16, and 15 and 17 a heat refractory wall 75 is interposed. With the dividing wall 75 the rate of heating of the side-wall tubes is entirely independent of the rate of heat application to the side-wall tubes within the fire chambers 14 and 15. More specifically, the fire chambers 16 and 17 may be operating at much higher temperatures than the fire chambers 14 and 15. Control as between the two chambers is entirely independent as shown in Fig. 3. The tubes of adjacent banks such as the double row of chambers 10 and 12 are staggered so that opposite sides of each row of tubes receives radiant heat. There is heat application throughout the larger part of the circumferential area of each tube. With the wall

75 the staggered relationship is obviously unnecessary though it has been illustrated. The inclusion of the wall 75 also indicates that the present invention may be utilized in the construction of a heater consisting only of the fire chamber 16 and 17. With such a heater the common convection section would ordinarily be replaced; by an air preheater suitably connected to the burners; or by a small convection section; or a steam superheater may be utilized to lower the temperature of the combustion gases leaving the fire chamber corresponding to 16 and 17.

With the foregoing understanding of the principles underlying the present invention, other modifications and embodiments will suggest themselves. For example, there has been indicated in the horizontal sectional view of Fig. 6, the application of the present invention to a single end-fired heater in which still burning gases from burners 76 are by an elongated muffle 76a directed as a moving rectangular column of gases intermediate the vertical banks of horizontally disposed tubes 77 and 78 and toward deflecting baffle structure 79. This baffle structure comprises self-supporting refractory walls having a rounded end 80 opposite the muffle 76, and side-walls 81 and 82 which serve to maintain the combustion gases in contact with tubes 77 and 78 for a substantially longer time than is indicated in the preceding embodiment of the invention. Instead of utilizing the space enclosed by the walls forming the structure 79 the internal flue in this embodiment of the invention is formed by a part of the end wall 83 and by a complementary wall 84. Between the two semi-cylindrical sections of walls 83 and 84 a vertical internal flue 85 is provided. Vertical outlet passages 86 and 88 are provided between the walls 83 and 84, these passages extending from the bottom to substantially the top of the heater. They lead into the internal flue 85. The flue 86 forms a part of a stack, the one being but a continuation of the other. Hence, the lower part 85 of the built-in stack applies a stack draft, as described in connection with the preceding embodiment of the invention, to the fire chamber.

In order to accentuate the compensating effect of the changing draft from the bottom to the top of the internal flue, the respective passages leading to the internal flue may be tapered or wedge-shaped, with the base portion wider than the top. Such a wedge-shaped passage 86 is illustrated in Fig. 7, and the passage 88 is identical. Such wedge-shaped outlet openings at passages 56 provide constantly changing openings through which the gases pass into the internal flue or the built-in stack 85. Though my invention in its several forms is not necessarily limited thereto, the inclination from the vertical of each side-wall of these openings or passages may be of the order of 0 degrees to 2 degrees.

With heaters constructed as above described and explained, widely differing heating fluids such as gaseous hydrocarbons and heavy residuum may be heated according to any desired time-temperature and pressure relations. The application of heat in each of the fire chambers 10-17, Figs. 1-4, may be at materially different rate than in the other fire chambers. For other applications, different streams of petroleum may be heated in each pair of fire chambers. For example, the fire chambers 10 and 11 may be utilized to heat a stream of oil to a temperature which will produce vapors. The derived vapors may then be superheated in the tubes of the fire

chambers 12—15, while the unvaporized oil may be simultaneously subjected to time and temperatures in the tubes of fire chambers 16 and 17 which will produce viscosity reduction thereof. In the heating of vapors it will be seen the present construction particularly adapts itself to the connection of a plurality of tubes in parallel one with the other. As will be best understood by those skilled in the art, the pressure drop may be reduced tremendously in this manner. The present invention leads itself to the use of conventional headers for connecting the tubes in parallel, in avoidance of specially designed headers whose first costs and replacement costs may be very substantial.

What is claimed is:

1. A fluid heater comprising a plurality of horizontal tubes forming a pair of vertical banks spaced one from the other with a relatively long tube-free fire chamber therebetween, a plurality of burners spaced vertically one above the other for directing streams of combustion gases intermediate said banks of tubes and generally parallel to their longitudinal axes, means for producing equalized flow of gases from the bottom to the top of said chamber comprising internal chimney structure having an opening shielded from the view of said burners and through which from the floor to the roof of said fire chamber said gases flow, and means connected to said chimney structure for applying a stack-draft thereto.

2. A fluid heater comprising a plurality of horizontal tubes forming a pair of vertical banks spaced one from the other with a relatively long tube-free fire chamber therebetween, a plurality of burners spaced vertically one above the other for directing streams of combustion gases intermediate said banks of tubes and generally parallel to their longitudinal axes, internal chimney structure spaced inwardly from said banks and extending from the floor to the roof of said fire chamber, said structure having narrow openings on opposite sides thereof which sides are normal to the direction of flow of said gases, and which openings extend from the floor to the roof of said fire chamber, and means connected to said chimney structure in the region of said roof for applying a stack-draft thereto.

3. In a fluid heater having a plurality of horizontal tubes forming a pair of vertical banks spaced one from the other with a relatively long tube-free fire chamber therebetween, and a plurality of burners spaced vertically one above the other for directing streams of combustion gases intermediate said banks of tubes and generally parallel to their longitudinal axes, the combination of means for producing equalized flow of said gases from the bottom to the top of said chamber comprising internal chimney structure spaced inwardly from said banks and one portion of which extends toward said burners, said structure in a region adjacent each of said banks and generally at right angles to the axes of said tubes having an elongated opening which extends from substantially the bottom to the top of said fire chamber for egress of gases from said fire chamber.

4. The combination as set forth in claim 3 in which the openings on opposite sides of said chimney structure vary uniformly from a relatively wide opening near the floor of said fire chamber to a substantially narrower opening near the top of said fire chamber, said openings being substantially in the form of tapering slots.

5. A fluid heater comprising a plurality of hori-

zontal tubes forming a pair of vertical banks spaced one from the other to form therebetween a tube-free chamber relatively long as compared with its width, an internal chimney structure disposed intermediate the ends of said chamber for dividing it into two fire chambers, said structure comprising refractory walls which from the bottom to the top of said chamber extend substantially across said chamber, said walls in the regions respectively adjacent said banks having a spacing between said walls for the flow of gases into the internal chimney structure in a direction generally at right angles to the axes of said tubes, and a plurality of burners at opposite ends of said chamber and spaced vertically one above the other for directing streams of combustion gases intermediate said banks of tubes, generally parallel to their longitudinal axes, and toward said internal chimney structure.

6. The combination as set forth in claim 5, in which said internal chimney structure comprises separate refractory walls both of which extend across the chamber and which approach each other in the regions adjacent said banks to form elongated openings from the bottom to the top of said chamber, and means cooperating with both of said walls to apply a stack-draft to the space between said walls.

7. A combination as set forth in claim 5, in which said internal chimney structure comprises separate refractory walls both of which extend across the chamber and which approach each other in the regions adjacent said banks to form elongated openings from the bottom to the top of said chamber, said openings being wider near the bottom of said chamber and progressively narrower toward the top of said chamber, and means cooperating with said internal chimney structure to apply a stack-draft to the space between said walls.

8. A fluid heater comprising a plurality of horizontal tubes forming a pair of vertical banks spaced one from the other to form therebetween a tube-free chamber relatively long as compared with its width, internal flue structure intermediate the ends of said chamber and extending from the bottom to the top thereof, said structure comprising refractory walls which from positions adjacent each other and one bank of said tubes respectively extend generally toward the opposite ends of said chamber and from positions midway of said chamber again extend toward each other to positions spaced one from the other and from the other of said banks thereby to form between said walls an internal flue, means connected to the top of said internal flue for subjecting the interior thereof to a stack-draft for withdrawal of gases through the spaces between said walls in the regions where they approach each other, and burners intermediate the respective ends of said chamber for directing combustion gases toward said internal flue and intermediate said banks of tubes.

9. A fluid heater comprising refractory walls, a floor and a roof, a plurality of vertical banks of horizontal tubes extending across said heater and forming therebetween a plurality of tube-free chambers which are relatively long as compared with their width, an internal chimney structure disposed intermediate each of said chambers, each of said structures consisting of a pair of walls which approach each other in the regions adjacent the two banks of tubes in each chamber for withdrawal of gases between said walls, a convection section disposed above and

interconnecting said internal chimney structures, said convection section including a plurality of fluid-conducting tubes extending horizontally thereacross in directions generally normal to the direction of said first named banks of tubes and means for applying a stack-draft to said convection section and to said internal chimney structures.

10. A fluid heater comprising a plurality of horizontal tubes forming a pair of vertical banks spaced one from the other with a relatively long tube-free fire chamber therebetween, a plurality of burners spaced vertically one above the other for directing combustion gases intermediate said banks of tubes and generally parallel to their longitudinal axes, means for producing equalized flow of gases from the bottom to the top of said chamber comprising a built-in stack, half of the lower part of which is formed by an end-wall of the heater, and the other half of which is formed by a second wall, said second wall cooperating with said end-wall to form a narrow elongated opening extending from the bottom to the top of the heater and communicating with the upper part of said stack.

11. The combination as set forth in claim 10 in which said second wall cooperates with said end wall to form a pair of openings which extend from the bottom to the top of said fire chamber at opposite sides thereof and which respectively communicate with said stack. 30

12. The combination as set forth in claim 10 in which said second wall cooperates with said end wall to form a pair of openings of progressively narrower cross-sectional area from the bottom to the top of said fire chamber and which communicate with said stack, said openings being disposed at right angles to the direction of the flow of gases from said burners.

13. A fluid heater comprising a plurality of horizontal tubes forming a pair of vertical banks spaced one from the other with a relatively tube-free fire chamber therebetween, a plurality of burners spaced vertically one above the other, a vertically elongated combustion chamber of relatively narrow width compared with its vertical height for receiving combustion gases from said burners and for directing them intermediate said banks of tubes and generally parallel to their longitudinal axes, means for producing equalized flow of gases from said elongated combustion chamber upwardly and vertically through said chamber comprising internal chimney structure having an opening shielded from view of said burners and of a configuration such as to apply a greater stack-draft near the lower portion of said chamber than at the upper portion thereof, and means connected to said chimney structure for applying a stack-draft thereto. 25

FRANK H. PRAEGER.
